COIN CONTROLLED MECHANISM

Burns S. Watling, Chicago, Ill., assignor to
Watling Scale Company, Chicago, Ill., a corpora-
tion of Illinois

Application June 30, 1938, Serial No. 216,652

7 Claims. (Cl. 194—92)

This invention relates to coin controlled mechanism, such as is extensively used in connection with vending machines that vend articles such as candy, chewing gum etc., upon the deposit of a proper coin and the actuation of a handle or lever. Such machines commonly employ a mechanism that locks the article delivery mechanism inoperative until or unless a proper coin has been deposited to unlock or release the locking mechanism, the delivery mechanism being automatically re-locked after each actuation.

So far as I am aware, such machines have hitherto been built to operate only with coins or tokens of uniform size, such as a penny or a nickel, although some machines selling merchandise or service of different values, such as a nickel, a dime and a quarter are known, but these machines have hitherto required separate and distinct coin chutes and coin-controlled mechanisms for controlling the vending mechanism. This makes the production of such multiple coin machines quite expensive, as compared with a single coin machine. In the case of a single coin machine, if a customer has not the particular coin required, he must first get change, and this is not always readily available or convenient.

An important object of this invention has been to provide, for association with a vending machine or the like, a coin-controlled mechanism employing a single coin chute and lock controlling mechanism that may be operated with a plurality of coins of different sizes and value, provided the larger size coin is an even multiple in value of a smaller sized coin. For example, the price of the merchandise or service may be five cents, but a customer may have no smaller coin than a quarter. Or, the price of the merchandise or service may be a penny, but the customer may have no pennies, but a nickel. In such cases the customer, instead of getting his quarter or his nickel changed into nickels or pennies, may deposit a larger coin, and this will release the locking mechanism for five successive operations, so that the customer can obtain goods or service to the full value of the deposited larger coin.

I have herein disclosed the invention as embodied in a type of check exhibitor coin-controlled apparatus disclosed in Letters Patent to T. W. B. Watling, No. 2,015,640, September 24, 1935, and No. 2,038,069, April 21, 1936; but the broad principle of the invention is adaptable to other types of coin-controlled mechanism.

In the accompanying drawings I have disclosed

an apparatus embodying the invention and adapted to function in the manner above described with nickels and quarters; and referring thereto—

5 Fig. 1 is a front elevation of the improved coin chute; the casing of the machine being omitted.

Fig. 2 is a perspective of a pair of cooperating levers that are mounted on the front of the coin display member and cooperate with the larger diameter coin to determine the number of successive operations of the vending machine that can be obtained by the use of the larger diameter coin.

10 Fig. 3 is a rear elevation of the parts shown in Fig. 1.

Figs. 4 and 5 are sectional details taken on the line 4—5 of Fig. 1, illustrating different positions of a deflector member designed to prevent the jamming of the machine by a second coin deposited before the preceding coin has left the operating position.

15 Fig. 6 is a perspective of the deflector shown in Figs. 4 and 5 isolated from its support.

Figs. 7 and 8 are front elevations, with some of the covering parts appearing in Fig. 1 removed to disclose underlying structure; these figures illustrating different operating positions of the levers shown in Fig. 2 which are operated only by the larger coin.

20 Fig. 9 is a view in front elevation, similar to Figs. 7 and 8, but with the levers and still further covering parts removed to clearly disclose the routes by which each coin enters and leaves the circular pathway of the check exhibitor or display member.

25 Fig. 10 is a fragmentary view of the lower right-hand portion of Fig. 9, showing a check or coin in the operating position or first station of the annular display guideway.

Fig. 11 is a fragmentary cross-sectional view taken on the line 11—11 of Figs. 1 and 10.

30 Figs. 12 and 13 are views similar to Fig. 11, but showing the pin which controls the operation of the latch lever in different positions.

Fig. 14 is a side elevation of the check control apparatus and of the lock and release mechanism that controls the article delivery mechanism, a fragment of the casing appearing in vertical cross-section.

35 Fig. 15 is a vertical transverse section, taken on the line 15—15 of Fig. 3.

A fragment of the machine casing is shown at 40 15 in Fig. 14. Within this casing is a main supporting frame 16, to the upper portion of which is secured a frame plate casting 17 best shown in

outline in Figs. 3, 7 and 8. This frame plate 17 is formed with a circular opening 18 constituting the outer boundary of the check exhibitor opening. Attached to the upper right-hand corner portion of the plate 17, as by screws 19 and 20 (Fig. 3) is an arcuate chute structure comprising an inner relatively thick plate 21 in which is formed a coin channel 22 indicated by dotted lines in Fig. 1, and upper and lower covering plates 23 and 24 secured as by screws 25 and 26 to the plate 21. In the upper end of the casing 15 is a coin inlet hole 27 (Fig. 14) aligned with an annular cup 28 that registers with the upper end of the coin chute. As indicated in Fig. 1, the lower end of the coin chute is divided or forked to provide a coin passageway 29 leading to the circular exhibitor and a discharge passageway 30 leading to the upper end of a vertical discharge 31 for iron slugs diverted and thrown out by the usual magnet 32.

The coin display assembly, which is shown in cross-section in Fig. 15 includes a spider 33 secured to the back of the frame plate 17 by screws 33'. In the hub of the spider is a bearing 34 having front and rear circular flanges 36 and 37 apertured at top and bottom for the passage of fastening screws 38 (Figs. 7, 8 and 15) which engage tapped holes 39 (Figs. 3 and 15) in the hub of the spider 33. On the rear of the flange 37 is a bearing 40 for a coin conveyor wheel 41 which is formed with radial arms 42 terminating in forwardly bent portions or fingers 42' which extend across the coin pathway and are spaced to receive the coins between them. By reference to Figs. 1, 7, 8 and 9, it will be seen that the fingers 42' both effect and limit the simultaneous step-by-step movements of the coins through the pathway. On the forward end of the bearing 34, is mounted a disc 43 that bears against the front face of the flange 36, the peripheral portion of said disc forming the inner portion of the rear wall of the coin pathway. Next to the disc 43, is a spacer member 44 having the shape shown in Fig. 9, the periphery of which defines the inner transverse wall of the coin pathway. Covering the spacer 44, is a front plate 45 having the outline shown in Figs. 7 and 8. The screws 38 pass through registering holes in the parts 44, 43, 36 and 37 into the tapped holes 39 of the spider 33. The front plate 45 is secured to the underlying spacer 44 by screws 46 (Fig. 1) passing through holes 47 (Fig. 7) in plate 45 and into tapped holes 48 (Fig. 9) in the spacer 44, the screws 46 also serving for the mounting of a front plate 49 (Fig. 1), bearing indicia of the coins usable in the machine. By reference to Fig. 15 it will be seen that the front portion of the frame plate 17 surrounding the hole 18 forms the outer portion of the rear wall of the coin passageway. The outer transverse wall of the coin passageway is formed by a spacer ring 47'. The outer portion of the front wall of the passageway is formed by a ring 50 having its inner peripheral portion overhanging the outer transverse wall of the passageway. The rings 47' and 50 are secured to the frame plate 17 by screws 51.

Referring to Fig. 9 it will be seen that the ring 47' surrounding the coin pathway and forming the outer transverse wall thereof is interrupted or cut away at 52 to provide an outlet for the coins into a vertical depending coin delivery chute 53. Also, the coin guiding periphery of the spacer 44 is formed with an outwardly and downwardly directed extension 54 which directs the discharging coins into the chute 53.

Referring to the means for directing the coins from the branch 29 of the main coin chute into the circular pathway of the coin exhibitor, by reference to Figs. 9 and 10 it will be seen that the spacer 44 is formed with a peripheral cut-out 55 just behind the extension 54 which, with the underlying disc 43 forms in part a pocket, the front wall of said pocket being formed by a raised hood 56 (Figs. 7 and 8) on the front plate 45. The open end of this hood registers with the lower end of the coin chute branch 29, and receives the coins from branch passage 29 and delivers them to said pocket, said lower end overlapping the coin ejector extension 54. A coin temporarily arrested in said pocket drops onto the coin receiving portion 57 of the outer transverse wall of the circular pathway, as shown in Fig. 10. This first position in the circular coin pathway is the so-called operating position because in this position the coin cooperates with a plunger, later described, which controls the operating mechanism of the machine.

Several ejectors are employed, in addition to magnet 32, for ridding the machine of spurious tokens, such as bent coins, undersized coins, buttons and the like, with which dishonest users attempt to cheat the machine. On the rear of the upper portion of the plate 21, is pivotally mounted a gate 58 (Fig. 3) urged to closed position by a torsion spring 59 opposite the channel 22 and properly spaced from the opposite wall of the channel by a regulating screw 60 to allow the passage of a proper coin. This gate 58 can be swung open to remove a spurious token by means of an elbow lever 61 (Figs. 1 and 14) pivoted at 62 on a lug 63 on the cover plate 23, the upper end of said lever being formed with a nose 64 movable through a slot 65 in the plates 21 and 23 and bearing against an upstanding lug 66 (Fig. 3) on the gate. The other arm of the lever, as shown in Fig. 14, extends rearwardly across an edge of the plates 21 and 23 and terminates in a downwardly and rearwardly inclined portion 67 adapted to engage a plunger 68 for rocking the lever 61 to open the gate 58.

The machine shown is designed to be operated by a nickel or a quarter, and coins of smaller size such as a penny or a dime are thrown out by a gravity switch 69 (Fig. 1) pivoted at 70 on the outer end of the lug 63, the depending portion of the switch extending into the coin chute through a slot 71 in the plate 23 across the path of the coin and formed with an inclined edge to deflect the small coin out of the main coin chute. A forwardly projecting arm 72 serves as a counter-weight to hold the switch in operative position. This switch will permit the passage of a legitimate coin without ejecting the latter, since the slotted portion of the rear wall of the chute opposite the switch 69 is under-cut to confine the edge portions of a legitimate coin.

If a legitimate coin is inserted into the machine before the previously inserted coin has left the operating position, the subsequently inserted coin is diverted and ejected by means of an automatic throw-out switch located at the lower portion of the branch 29 of the main chute. This switch is shown in assembled position in Fig. 1 and in structural detail in Figs. 4, 5 and 6. By reference to Fig. 1, it will be seen that the cover plate 24 is formed with a rectangular cut-out 73 large enough to pass a quarter therethrough and of course large enough to pass a nickel. A lug 74 upstanding from the forward portion of the lower edge of the cut-out, narrows the width of

the latter sufficiently to prevent accidental discharge of coins at this point. In the back wall of the chute 29 is a smaller rectangular opening 75 that affords play for an inclined deflector plate 76 on the free end of an arm 77 which is mounted on a pivot pin 78, the latter extending through ears 79 on the arms 77 and through similar ears 80 formed on a mounting member 81. This mounting member is formed with a pair of ears 82 that lie between cooperating ears 83 on the inner lower corner of the plate 24, the pairs of ears 82 and 83 being connected by a pivot pin 84. Encircling the pivot pin 78 is a torsion spring 85, having one end secured to a lug 85.1 on the arm 77. Integral with one of the ears 80, is a laterally extending arm 86 which is normally maintained by gravity obliquely across the path of travel of the coins entering the channel of the circular exhibitor just below the coin pocket, so that a coin dropping from the latter into the first position wipes behind the arm 86 and swings the deflector switch from the position shown in Fig. 4 to that shown in Fig. 5, wherein the switch is then effective to deflect a coin following too soon and so prevent jamming. To better insure the deflection of the coin, the outer edge of the deflector plate 76 and its arm 77 is equipped with an upstanding cam 87 which, in cooperation with an upstanding lug 88 (Fig. 1) on the forward edge of the opening 73 opposite cam 87, insures the 30 ejection of a coin displaced by the deflector 76. A slot 45' formed in the front plate 45 permits play of the arm 86 therethrough, and a depression 43' (Fig. 9) in the front face of the disc 43 behind the slot 45' insures an ample outward swing of the arm 86 through engagement of the coin with its rounded outer side to force the coin deflector into operative position. The deflected coin drops onto and slides down a delivery apron 89 (Fig. 1) formed as a bent up portion of the cover plate of the slug discharge 31.

The two-part, spring-biased structure of the deflector last described adapts it to function equally well with coins of different thickness. Also, the last described deflector is cooperatively associated with the mechanism later described by which, when a coin of greater value than the price of a single article delivered by the machine is inserted, the latch or lock of the operating mechanism is held released so that the latter can be actuated a sufficient number of times to effect delivery of articles to the full value of the deposited coin.

Referring to Figs. 3 and 14, the rotary coin conveyor 41 is intermittently actuated in one direction by an operating link 90. The upper end of the link 90 is pivotally connected to a vertically reciprocable bar 91 having slots 92 for receiving guide pins 93 secured to the rear face of the frame plate 17. Pivoted at 94 on an arm 95 on the inner edge of the bar 91, is a driving pawl 96 which is adapted to be carried downwardly into engagement with an arm 42 of the conveyor wheel for rotating the conveyor one step. The pawl 96 is normally held against a stop 97 on the arm 95 by means of a spring 98 which permits the pawl to pivot on the upstroke of the bar 91. In order to prevent reverse movement of the conveyor wheel and also for the purpose of properly positioning the conveyor after each operation, the conveyor has circumferential pockets 99 between adjacent arms 42 co-acting with a detent pawl 100 which is pivotally mounted on the frame plate 17 by a pin 101. A spring 102 holds the 70

pawl 100 in yielding engagement with the conveyor.

Briefly describing the coin-controlled mechanism by which the article delivery mechanism is normally locked against operation and is released upon the deposit of a proper coin, and referring to Figs. 9 to 14 inclusive, 103 designates a pusher pin or plunger which is slidable through a bearing 104 in the frame plate 17 and through a registering hole 105 in the ring 59. As shown in Fig. 9, the plunger 103 lies opposite the coin receiving end portion 57 of the coin pathway at the first station, the plunger 103 being outside the path of the fingers 42 of the conveyor wheel. When a coin is located at the first station, as shown in Figs. 10 and 11, the inner end of the plunger bears against the coin eccentrically of the latter, see Fig. 11. If no coin is present, the plunger passes through and substantially beyond the hole 105, as shown in Fig. 12, and in this position of the plunger the machine is locked against operation. The plunger 103 is mounted on the upper end of a latch lever 106 (Fig. 14) which is pivoted at 107 on the frame 16. This latch lever is normally urged in a direction to move the plunger 103 inwardly by a pull spring 108. Pivoted at 109 on the frame 16, is a bell crank lever 110 which is normally urged upwardly by a pull spring 111. When the bell crank 110 is rocked downwardly to its full extent, the article delivery mechanism is actuated. Formed in the inner edge of the latch bar 106, is a notch 112 for receiving a lug 113 on the bell crank 110 to prevent a complete stroke of the bell crank when the latch has not been disabled by a proper coin. Formed on the inner edge of the latch bar 106 just above the notch 112, is a cam 114 adapted to co-act with the lug 113 to hold the latch retracted as shown in Fig. 14 when the lever 110 is in its upper position. Mounted on the lever 110, is a pin 115 extending through a slot 116 in the link 90. A pull spring 117 is connected to the pin 115 and to the link 90 for normally holding the link in the position shown in Fig. 14. The construction is such that the latch permits a limited downward movement of the lever 110 without the use of a coin, that is, the lever 110 may move until the lug 113 rides down the cam 114 into the notch 112. But to permit a complete stroke of the lever 110 the latch bar 106 must be retained in its full retracted position shown in Fig. 14 against the action of the spring 103. This is accomplished by the engagement of the plunger 103 with a coin in the first station of the display chute, as shown in Figs. 10 and 11. Mounted on the forward end of the lever 110, is a pin 118 adapted to cooperate with lever actuating means which may be similar to that shown in my former Patent No. 1,990,719, issued February 12, 1935.

The last described lock and release mechanism preferably includes other automatic devices by which, if a check of the annular type is used, the machine will remain locked against operation. Said other automatic devices are also shown and described in the aforesaid Watling Patents 2,015,640 and 2,038,069, but since they form no part of the present invention, description thereof is unnecessary.

Describing next that feature of the invention which permits the use of coins or other tokens of different diameters and values in a single coin chute and display head and whereby, when the smaller coin or token is deposited the operating means of the article delivery mechanism is locked after each operation until another coin or token

is deposited, but when the larger coin or token is deposited the operating means of the article delivery mechanism may be successively operated as many times as the value of the larger coin or token is a multiple of the smaller coin or token before the operating means is locked, and referring mainly to Figs. 1, 2, 7 and 8, 119 designates as an entirety a primary elbow lever which is pivoted at 120 on the frame plate 17 just outside the ring 50. One arm 121 of this lever extends across the front of the coin pathway of the exhibitor and on its upper end carries a pin 122 which plays through a slot 123 in the front plate 45 and normally lies in such a position that the smaller coin, such as a nickel, will pass it without tilting the lever 119, but the larger coin, such as a quarter, will engage it and rock the lever to the position shown in Fig. 7, allowing the coin to then pass. Continuous with the outer edge of arm 121 is a shutter member 123' which, in relation to the plunger 103 and hole 105, plays an important part in maintaining the article delivery mechanism unlocked for several successive strokes, and continuous with the shutter member is a cam 124 that throws the coin throw-out switch 76, 77 into operative position whenever the lever arm 121 is rocked upwardly, as shown in Figs. 4 and 5. A pull spring 125 anchored to the frame plate 17 and to a lug 126 on the shank of cam 124 urges the lever 119 to its normal position shown in Figs. 1 and 8. The other straight arm 127 of lever 119 has on its free end a lateral hook 128.

A similar secondary elbow lever, designated as an entirety by 129, is pivoted at 130 on the frame plate 17 just outside the ring 50, and, in this instance, about 90 degrees beyond the pivot 120 of lever 119. One arm 131 of this lever extends obliquely across the ring 50, and on its free end carries a pin 132 that plays through a notch 133 in the ring 50, and normally lies outside the path of travel of both the smaller and larger coins (Fig. 1). The depending arm 134 of this lever has formed on its outer edge, slightly above its lower end, a cam 135 that is normally engaged by the hook 128, as shown in Figs. 1 and 2, and at the bottom of the cam 135 is a stop shoulder 136 that prevents clockwise swing of lever 119 while the larger coin is traveling from pin 122 to pin 132. A pull spring 137 anchored to the frame plate 17 and to the lower end of lever arm 134 urges lever 129 in a clockwise direction.

Describing the operation, with the levers and their pins positioned as shown in Fig. 1, so long as the smaller coins only are fed to the machine the levers 119 and 129 remain idle, since the smaller coins will pass the pins 122 and 132 without contacting the latter, or without displacing the pins sufficiently to disturb the relative position of the levers shown in Fig. 1. If, however, a larger coin is fed to the machine, as it is advanced by a finger 42' one step beyond the first station it will thrustingly engage the pin 122 and rock lever 119 counterclockwise to the position shown in Fig. 7. The hook 128 rides down off the cam 135 and comes to rest against the shoulder 136 under the pull of spring 125, and at the same time spring 137 rocks lever 129 slightly clockwise carrying pin 132 into the path of the larger coin. Simultaneously with this shift of the two levers, the cam 124 rises from the position shown in Fig. 4 to that shown in Fig. 5, swinging the coin throw-out switch 75

76, 77 into operative position so that, if a coin, either large or small, is deposited in the chute before the large coin has passed the pin 132, it will be diverted and returned to the depositor. 5 Also, this counter-clockwise swing of lever 119 carries the shutter 123' from its open or idle position shown in Figs. 8 and 11 to its closed or operative position shown in Figs. 7 and 13, wherein it covers the hole 105 and blocks the passage of plunger 103, thus preventing the operation of latch lever 106 and maintaining the operating mechanism unlocked until lever 119 has been restored to its normal position (Fig. 1). If, as in the instance shown, the customer has deposited a twenty-five cent piece, and the machine is loaded with articles valued at five cents each, he can manipulate the delivery mechanism five times in succession before the machine becomes locked. As the larger coin is forced past the pin 132 on the fifth operation, it swings lever 129 to the dotted line position shown in Fig. 8. This carries the stop shoulder 136 clear of the hook 128 and permits spring 125 to return lever 119 to normal position and spring 137 to return lever 129 to normal position, restoring both levers to the positions shown in Fig. 1, and also restoring the normal functions of plunger 103 and throw-out switch 76, 77.

A keeper 138 (Figs. 11, 12 and 13) attached to the frame plate 17 overlaps the lever arm 121 to guard against lateral displacement of the latter if pivot pin 120 should work loose.

When the coins reach the end of their passage through the circular guideway, they are deflected by the finger 54 into the discharge chute 53 and, at the lower end of this discharge chute, means may be provided for separating the coins of larger diameter from those of smaller diameter.

40 The upper portion of the chute 53 is of sufficient width to receive all coins, as shown in Fig. 9, but the lower portion thereof permits the passage only of the smaller coins. The larger coins come to rest on shoulders 139 (Fig. 1) between which the smaller coins drop. The larger coin is secured against accidental displacement from the shoulders 139 by means of a gate 140 hinged to the frame by a pivot pin 141, and normally urged into effective position by a spring 142 which embraces the pin 141. The larger coin is ejected through an opening 142' in the discharge chute into a suitable receptacle, not shown, by an ejecting pin 143 which is actuated upon each operation of the delivery mechanism.

55 The smaller coins are intercepted by a lug 144 formed on the lower end of a lever 145 which is pivoted to the chute by a pin 146. The lug 144 is normally held in effective position by means of a spring 147 connected to the chute and to a lug 148 on the lever. The lever 145 carries an arm 149 which is pivotally secured to the lever by a pin 150.

60 Formed on the upper end of the arm 149, is a lug 151 (Fig. 7) adapted to enter the chute to serve as a stop for preventing more than one coin at a time from occupying the ejecting position. Mounted on the lever 145, is a stop 152 against which the arm 149 normally is urged by a spring 153.

65 The lever 145 is actuated upon each operation of the delivery mechanism by means of a cam 154 which is carried by the reciprocal bar 91 in position to strike the stop 152 for rocking the lever 145 against the action of the spring 147.

The smaller coin is held against accidental displacement from the lug 144 by means of a spring pressed gate 155 pivotally secured to the chute by a pin 156. Solid coins are ejected by means of a plunger 157 which is actuated upon each operation of the delivery mechanism. If the small coin is apertured, the plunger 157 will pass through it and, upon the retraction of the plunger and the lug 144, the coin will drop through the lower end of the chute. In this manner, solid coins may be separated from apertured ones.

The term "coin" as used in the following claims is intended to include not only true coins of the realm but also checks or tokens such as, under the laws of some states and municipalities, may be purchased from the owner or operator of the machine and used in the latter in lieu of coins.

Although but one specific embodiment of this invention has been herein shown and described, it will be understood that certain details of the construction shown may be altered without departing from the spirit of the invention as defined by the following claims.

I claim:

1. In a mechanism of the class described, the combination of a coin pathway, means for both effecting and limiting simultaneous step-by-step movements of relatively larger and smaller diameter coins through said pathway, coin-controlled means for locking said last named means against operation when no coin has been deposited, said locking means being disabled by each successive deposited coin of smaller diameter, and means associated with said pathway and actuated only by a coin of larger diameter as it is advanced through said pathway operative to maintain said locking means disabled for a predetermined number of actuations of said movement effecting means, said means associated with said pathway including means for restoring said locking means to operative condition at the conclusion of said predetermined number of actuations of said movement effecting means.

2. In a mechanism of the class described, the combination of a coin pathway, means for both effecting and limiting simultaneous step-by-step movements of relatively larger and smaller diameter coins through said pathway, coin-controlled means for locking said last named means against operation when no coin has been deposited, said locking means being disabled by each successive deposited coin of smaller diameter, and means associated with said pathway and actuated only by a coin of larger diameter as it is advanced through said pathway operative to maintain said locking means disabled for as many actuations of said movement effecting means as the larger diameter coin is a value multiple of the smaller diameter coin, said means associated with said pathway including means for restoring said locking means to operative condition at the conclusion of the stated number of actuations of said movement effecting means.

3. In a mechanism of the class described, the combination of a coin pathway, means for both effecting and limiting simultaneous step-by-step movements of relatively larger and smaller diameter coins through said pathway, coin-controlled means for locking said last named means against operation when no coin has been deposited, said locking means being disabled by each successive deposited coin of smaller diam-

eter, a movable member associated with said pathway and a spring urging said movable member sufficiently into said pathway to be struck and displaced only by a coin of larger diameter, means actuated by said movable member when the latter has been displaced by a coin to maintain said locking means disabled for a predetermined number of actuations of said movement effecting means, a second movable member associated with said pathway beyond said first named movable member and a spring urging said second movable member sufficiently into said pathway to be struck and displaced by said coin of larger diameter, and connections between said movable members through which the displacement of said second movable member by the coin restores said locking means to operative condition.

4. An embodiment of claim 3, wherein the means actuated by the first named movable member when the latter has been displaced by a coin maintains the locking means disabled for as many actuations of the movement effecting means as the larger diameter coin is a value multiple of the smaller diameter coin.

5. In a mechanism of the class described, the combination of a frame having a coin-exhibit pathway, means for both effecting and limiting simultaneous step-by-step movements of relatively larger and smaller diameter coins through said pathway, coin-controlled means for locking said last named means against operation when no coin has been deposited, said locking means being disabled by each successive deposited coin of smaller diameter, primary and secondary levers pivoted intermediate their ends on said frame adjacent to, and at spaced points along, said pathway, one arm of each lever carrying a pin movable into and out of said pathway, springs respectively urging said levers in directions to shift said pins into the path of a larger diameter coin moving through said pathway, inter-controlling connections between said levers through which the tilting of each by a larger diameter coin acting on its pin permits the tilting of the other lever, under the urge of its spring, in the reverse direction, and means associated with one of said levers and said pathway operative, when the pin of said primary lever has been displaced by said larger diameter coin, to maintain said locking means disabled until said larger diameter coin has encountered and displaced the pin of said secondary lever.

6. In a mechanism of the class described, the combination of a frame having a coin-exhibit pathway, means for both effecting and limiting simultaneous step-by-step movements of relatively larger and smaller diameter coins through said pathway, coin-controlled means for locking said last named means against operation when no coin has been deposited, said locking means being disabled by each successive deposited coin of smaller diameter, primary and secondary levers pivoted intermediate their ends on said frame adjacent to, and at spaced points along, said pathway, one arm of each lever carrying a pin movable into and out of said pathway, springs respectively urging said levers in directions to shift said pins into the path of a larger diameter coin moving through said pathway, relatively movable interengaging means on the other arms of said levers through which each lever limits the spring-urged tilting movement of the other, and means associated with said primary lever and said pathway operative, when the pin of said primary lever has been displaced by said larger di-

ameter coin, to maintain said locking means disabled until said larger diameter coin has encountered and displaced the pin of said secondary lever.

7. An embodiment of claim 6, wherein the relatively movable interengaging means on the other

arms of the levers consist of a cam on one lever arm and a stop shoulder beneath said cam, and a hook on the other lever arm engaged with said cam in one position of said levers and with said stop in the other position of said levers.

BURNS S. WATLING.
